UNITED STATES PATENT OFFICE.

EMMIT G. LATTA, OF SYRACUSE, NEW YORK, ASSIGNOR OF ONE-HALF TO HARVEY A. MOYER,
OF SYRACUSE, NEW YORK.

LINE-SPACING MECHANISM FOR TYPE-WRITING MACHINES.

No. 926,126.

Specification of Letters Patent.

Patented June 29, 1909.

Application filed May 18, 1906. Serial No. 317,507.

To all whom it may concern:

Be it known that I, EMMIT G. LATTA, a citizen of the United States, residing at Syracuse, in the county of Onondaga and State of New York, have invented a new and useful Improvement in Line-Spacing Mechanisms for Type-Writing Machines, of which the following is a specification.

This invention relates more particularly to line spacing or platen rotating mechanisms for typewriting machines.

The primary objects of the invention are to produce a desirable mechanism for turning the platen to feed the paper and for setting back the carriage from either end of the carriage; to make the same of simple and economical construction; and to arrange the parts in close compact relation so that they will not project from the carriage in an objectionable manner.

Other objects of the invention are to provide guards to prevent accidental contact of the operator's hands or clothing with the line spacing mechanism; the provision of a platen brake and means actuated by the line space mechanism for releasing the platen detent to free the platen and for applying the brake to hold the platen frictionally in any position to which it may be turned; and to combine the carriage releasing devices with the line spacing mechanism in a novel manner, whereby the latter supports and guards the former.

Still another object of the invention is to improve the line spacing mechanisms for typewriting machines in the respects hereinafter described and set forth in the claims.

In the accompanying drawings, consisting of two sheets: Figure 1 is a broken plan view of a typewriter carriage provided with line spacing mechanism embodying the invention. Fig. 2 is an elevation, partly in section, of the left-hand end thereof. Fig. 3 is an elevation, partly in section, of the right-hand end thereof. Fig. 4 is a sectional elevation thereof in line 4—4, Fig. 1. Fig. 5 is a broken plan view, partly in section, of the connecting means for the line space levers at opposite ends of the carriage. Fig. 6 is an end sectional elevation of the platen and line spacing mechanism. Fig. 7 is a sectional elevation of the shaft of the line space lever and the connected parts. Fig. 8 is a fragmentary perspective view of the line space lever, its bearing bracket and con-

nected parts. Fig. 9 is a detached perspective view of one of the guard plates. Fig. 10 is a detached perspective view of the bearing bracket for the auxiliary line space lever. Fig. 11 is a detached perspective view of the pawl lifter and bearing sleeve to which it is attached. Fig. 12 is a detached perspective view of the adjusting arm for the pawl lifter, showing the inside thereof.

Like letters of reference refer to like parts in the several figures.

A, Fig. 1, represents the carriage of a typewriting machine and B the rotatable platen journaled thereon. The carriage preferably consists of vertical end plates *a* rigidly connected at the lower portions by a skeleton frame or casting *a*² and a front bar *a*³. The carriage is mounted to travel horizontally in the usual manner on suitable guide bearings, not shown. The platen B may be of the usual or any suitable construction. As shown, it is secured to a platen shaft *b* which is provided at its ends with the usual finger wheels *b*¹ for turning the platen, and is removably journaled on the carriage. Preferably bearing sleeves C C', Figs. 4 and 11, surround the shaft between the hubs of the end plates *b*² *b*³ of the platen and the hubs of the finger wheels. These bearing sleeves are cylindrical and rest in upwardly opening slots or seats *c*, Figs. 2 and 3, in the end plates of the carriage, and each sleeve is provided with spaced flanges or collars *c*' which bear against the opposite faces of the end plate. When the bearing sleeves are in position in their seats, the flanges fit closely against the opposite faces of the end plates to hold the sleeves and platen from longitudinal movement and to insure the proper alignment of the sleeves.

D D' represent guard plates arranged above the platen shaft at the opposite ends of the carriage for releasably holding the bearing sleeves for the platen shaft in their seats in the end plates. These guard plates D D' are pivoted at their rear ends by rivets *d*, or in any other suitable manner, to the rear upper portions of the carriage end plates and are provided with depending legs *d*', the lower ends of which bear on the bearing sleeves, between the collars thereof, to hold the sleeves in their seats. The guard plates are releasably held in the position shown in Figs. 2 and 3, by suitable means, for instance, by projecting teats *d*², Figs. 3 and 9, on their front ends which are adapted to snap into holes *d*³, 14

in upwardly projecting front lugs or portions on the carriage end plates. The teats are releasably retained in the holes by the resiliency of the guard plates D D', which are preferably made of spring metal. To permit the removal of the platen the front ends of the guard plates can be sprung inwardly to disengage the teats from the holes and then swung upwardly, as indicated by dotted lines in Fig. 2, when the platen with its shaft and bearing sleeves can be lifted off of the carriage. The central part of the guard plate D for the left-hand end of the carriage is preferably bent or offset inwardly, see Figs. 1, 4 15 and 9, whereby the plate overhangs portions of the line spacing mechanism, to be described, which are located between the left-hand end of the carriage and the adjacent end of the platen, and serves as a guard to prevent the contact of the hands or garments of the operator with the line spacing mechanism. The guard plate at the right-hand end of the carriage is also preferably similarly offset inwardly. The upper edges of the 25 guard plates are preferably horizontal and located slightly above the top of the platen and thus incidentally form supports for a ruler or other flat strip to be used as a shelf or support for the sheets in making erasures.

30 E E' represent two line space levers located at the opposite ends of the carriage, each lever having a vertical shaft or pivot e journaled in suitable bearings on the outside of the carriage end plates. The lever E at the 35 left-hand end of the carriage will be hereinafter referred to as the line space lever, and the other one E' as the auxiliary line space lever. The bearings for the line space levers are preferably formed by two outwardly projecting lugs e' on brackets e^2 e^3 which are riveted to the outer faces of the end plates of the carriage. The bearing brackets e^2 e^3 are of different shape, see Figs. 8 and 10, the one 40 e^2 for the line space lever having a third outwardly projecting bearing lug e^4 for a detent lever to be hereinafter described. An arm F fixed to the pivot of the line space lever projects through a hole f in the adjacent end plate, and is connected at its inner end by a 45 link f' to an upright pawl lever f^2 which is located between the end plate a and the adjacent end of the platen. The pawl lever is fulcrumed at its lower end, see Figs. 4 and 6, in any suitable way to a stud f^3 projecting inwardly from the end plate a and extends upwardly nearly to the top of the platen, being curved to pass the platen shaft. A pawl f^4 pivoted to the upper end of the pawl lever extends forwardly therefrom and is provided at 50 its front end with a laterally projecting toe f^5 adapted to engage the teeth of the ratchet wheel f^6 secured to the adjacent end plate of the platen in the usual or any suitable manner. The pawl lever and line space lever are 55 returned to the normal position after opera-

tion by any suitable spring, such as a coil spring f^7 surrounding the pivot stud for the pawl lever. A spring f^8 is secured to the pawl lever and bears at its free upper portion against a pin f^9 projecting laterally from the 70 depending heel or rear end of the pawl. This spring, which normally presses the toe of the pawl downwardly against the teeth of the ratchet wheel, is provided at its upper end with a bend or notch f^{10} adapted to receive 75 the pin f^9 on the heel of the pawl and hold the pawl in an upright position, shown by broken lines in Fig. 6, when the pawl is raised to this position to permit the removal of the platen from the carriage. By swinging the 80 line space lever E to the right the pawl lever and pawl will be swung rearwardly and will turn the ratchet wheel and platen. When released, the spring f^7 for the pawl lever will restore the parts to their normal position. 85

In order to prevent the platen from overrunning, without strain on the pawl, and provide a stop to limit the movement of the line space and pawl levers, and at the same time avoid parts projecting from the upper portion of the platen, the arm F of the line space lever E is provided with a projection G, Figs. 6 and 8, which strikes the ratchet wheel at the instant it has completed its movement and positively holds it against further movement. The stop G moves slower than the teeth of the ratchet wheel and it is adjusted to strike only the outer portion of one tooth so that the preceding tooth will not interfere with the stop as it moves into holding position. 95

The line space levers at the opposite ends of the carriage are operatively connected preferably as follows: H represents a horizontally connecting rod which is arranged 105 below the platen and is pivoted at its right-hand end to the end of an arm h fixed to the lower end of the pivot of the auxiliary line space lever. The other end of the connecting rod is pivoted to the front end of the arm 110 i of a detent lever I, Figs. 2, 5, 6 and 8, which is preferably pivoted at i' to the lug e^4 of the bearing bracket e^2 for the line space lever D. The arm i of this lever extends forwardly and downwardly from its pivot, and the lever has 115 another arm i^2 which extends inwardly through an opening in the carriage end plate a and then projects upwardly for actuating the detent for the ratchet wheel, as will be described. An arm k, Figs. 2, 5 and 8, is 120 fixed to the lower end of the pivot of the line space lever E and bears at its free end against the left-hand end of the connecting rod H. By this construction the line space lever E can be swung to the right to rotate the platen 125 without moving the connecting rod and auxiliary line space lever E', while the line space lever E will oscillate and will actuate the pawl lever to rotate the platen through the connecting rod and arm k when the auxiliary 130

line space lever E" is moved to the right. The auxiliary line space lever E' can be moved to the left without operating the other line space lever E for actuating a platen brake to be described. The auxiliary line space lever E' is preferably held in a normal central position by a spring l, Fig. 3, which surrounds the pivot thereof and bears at its opposite ends against the carriage end plate a' at opposite sides of the pivot. This spring is fixed to the shaft at its middle portion, for instance, by a clamp screw l' entering the pivot of the lever and bearing with its head against the central coils of the spring, and the spring acts to return the lever to the normal central position after movement in either direction. From Figs. 2 and 3 it will be seen that the line space lever E is longer than the auxiliary line space lever E', the object being to provide a long lever for those who prefer the lever to extend well forward, and a short lever for those who prefer that length, and also to provide in one machine a long lever that can be used to feed the paper without setting the carriage back and a short lever that can be used to set the carriage back without feeding the paper. To make this clear, it should be understood that with a carriage driving spring of the usual tension the long lever will operate the pawl to turn the platen before overcoming the resistance of the carriage driving spring, while the short lever will move the carriage before it turns the platen. But by pressure on the long lever after the platen is turned the carriage can be set back, and similarly the short lever can be made to turn the platen after setting back the carriage. Either lever may be used to both feed the paper for a new line and set back the carriage, while either function can be performed singly by the proper use of the intended lever.

The line space levers E E' can be interchanged for an operator desiring the long lever at the right-hand end of the carriage. In changing the levers the arms F and k are detached from the line space lever and applied to the auxiliary line space lever and the arm h of the latter applied to the former lever. The spring l for the auxiliary line space lever is of course used with the lever at the right-hand end of the carriage, and the pivot shaft of the line space lever is preferably provided with a hole l', Fig. 7, to receive the clamping screw l' for the spring l.

M, Figs. 1 and 6, represents a detent spring which is fixed at its upper end to an ear m projecting inwardly from the left-hand guard plate, and carries at its lower end a roller 60 which it presses against the teeth of the ratchet wheel. This detent serves the usual purpose of releasably holding the platen against rotation. As the detent roller normally rests against the ratchet wheel below 65 a line passing through the pivot for the guard

plate and the axis of the platen, it acts to hold the guard plate down in its normal position, and when the guard plate is raised for removing the platen, as above described, the detent spring will be flexed until the roller 70 passes the line mentioned and will then serve to hold the guard plate up, but it does not prevent the ready movement of the guard plate. This spring assists the snap fastener, before described, in securing the latter in its 75 normal position. The upwardly projecting arm i² of the detent lever I stands just in front of the projecting pintle of the detent roller, so that when said lever arm is oscillated rearwardly the detent roller will be 80 moved out of engagement with the ratchet wheel.

N, Figs. 3 and 4, represents a brake lever, preferably consisting of a rectangular frame, which is pivoted centrally to a spring n secured by a screw, or otherwise, to the right-hand end plate a' of the carriage. The inner end of the brake lever is preferably beveled and enters a beveled or V-shaped internal groove in an outwardly projecting annular 90 flange on the adjacent end plate b² of the platen, and the other end of the brake lever is located over the adjacent end of the connecting rod H. The connecting rod is provided beneath the outer end of the brake 95 lever with an inclined face n' and a notch n² at the upper end of the incline. When it is desired to apply the brake, the auxiliary line space lever E' is moved to the left, that is in the opposite direction from which it is moved 100 in line spacing. This moves the connecting rod H to the right, thereby sliding the inclined face n' beneath the outer end of the brake lever and forcing the latter upwardly. As the inner end of the lever bears on the 105 grooved flange of the platen it cannot descend and the supporting spring will be strained and will press the beveled inner end of the lever forcibly against the grooved flange of the platen, thus causing friction 110 enough to hold the platen in any position to which it may be turned. Normally the brake rests in the position shown in Fig. 4, and as its supporting spring is not strained at such time, the brake does not cause appreciable friction on the platen. The parts are so proportioned that when the outer end of the brake is engaged in the notch n³ on the connecting rod, it will be pressed therein by the brake spring n with sufficient force to hold 115 the brake and connecting rod against the tendency of the detent spring M and the returning spring f⁷ for the line space lever to return the parts to the normal position. When the brake is applied, as explained, the 120 movement of the connecting rod to the right will swing the detent lever I on its pivot and its upwardly projecting arm will move the detent M out of engagement with the ratchet wheel, so that the turning of the platen will 125 130

be opposed only by the friction brake. When the brake is released by the return of the auxiliary line space lever E' and the connecting rod to the normal position, the detent lever is also swung back to again permit the engagement of the detent with the ratchet wheel. O, Fig. 4, represents a pin or projection on the right-hand end of the connecting rod H adapted to strike the outer end of 10 the brake lever N just before the completion of the line space movement of the connecting rod, to swing the brake up so as not to interfere with the platen in removing and replacing it.

15 The auxiliary line space lever E' is used to effect the line space movement of the platen, to apply the brake N and remove the detent M, to release the brake and restore the detent, and to hold the brake out of the way in 20 removing and replacing the platen.

To regulate the operative movement of the platen turning pawl so that the platen can be turned for single, double or triple line spaces, an adjustable pawl lifter P is employed. The pawl lifter, see Figs. 4, 6 and 25 11, consists of an arm fixed to the inner end of the bearing sleeve C and having a segmental upper edge on which a rounded projection on the front end of the pawl is adapted to ride. 30 A spring arm p is also fixed to the inner end of the bearing sleeve and extends outwardly and upwardly, having at its upper end a tooth p', Fig. 12, adapted to snap into either of three notches p², Figs. 2 and 9, in the adjacent guard plate D. The spring arm also 35 has a projecting push button p³. The pawl lifter will hold the pawl off of the ratchet teeth until the pawl clears the pawl lifter, and by adjusting the pawl lifter toward or 40 from the pawl lever the effective movement of the pawl is lessened or increased. Thus by engaging the tooth of the spring arm p in the first, second or third notch p² the pawl will act to turn the platen for single, double 45 or triple line spaces. The pawl lifter is readily adjusted by pressing inwardly on the push button p³ to disengage the spring arm and then swinging the arm until its tooth snaps into the desired holding notch. By 50 this construction the line space adjusting device is located in favorable position for use, and entirely inside of the vertical plane of the carriage end plate, see Fig. 4, and does not project beyond the circumference of the 55 platen. It is out of the way and is easy and positive in action.

Attention is called to the fact that the described construction of the line space mechanism permits the use of paper as wide as the 60 distance between the carriage end plates. The paper passes under the rear parts of the 65 guard plates D D', detent M, pawl lever f² and arm k of the line space lever, and the brake N, and then upward in front of the offset central parts of the guard plates and

this is accomplished with all parts of the line space mechanism except the line space levers and the arms at their lower ends inside of the carriage end plates, thus leaving more than the usual room for grasping the platen finger 70 wheels.

Q, Fig. 1, represents the carriage feed rack bar arranged at the rear of the carriage and secured to the flattened rear side of a rod q which is fixed at its ends in any suitable 75 manner to the rear ends of carriage release levers R R' pivoted between their ends on studs r projecting outwardly from the end plates of the carriage. The rack bar is normally held in contact with the escapement 80 wheel (not shown) by springs r' coiled about the pivot studs for the levers. This is an ordinary arrangement of the levers, but to make the construction more compact and convenient, and to avoid the projecting 85 parts, the front ends of the carriage release levers project into slots s in the rear sides of the pivot shafts of the line space levers, see Fig. 7, and engage in slots t in push rods or stems T arranged to slide vertically in the 90 shafts of the line space levers, which for this purpose are made hollow. The rods T are provided at their upper ends with push buttons which occupy counter-bores in the hubs of the line space levers and project above the 95 levers. The engagement of the ends of the levers in the slots in the push rods prevents the detachment of the latter from the line space levers. The release bar is operated to release the carriage from its escapement, by 100 depressing either of the push buttons, and the push buttons are arranged in convenient positions for use. The front ends of the release levers are out of the way and guarded and less room is taken up than if the levers 105 were made with the usual flattened operating ends or finger pieces.

I claim as my invention:

1. In a typewriting machine, the combination of a carriage, a platen, a pair of line 110 space levers, and mechanism actuated by both of said levers for rotating the platen, one of said levers being movable independently of the other for actuating said mechanism, substantially as set forth.

2. In a typewriting machine, the combination of a carriage, a platen, line space levers arranged adjacent to the opposite ends of the carriage and having upright pivots, mechanism between one of said levers and 120 the platen for rotating the platen, and means for transmitting motion from the other lever to the first lever to actuate said mechanism, said first lever being movable independently of the other lever for actuating said mechanism, substantially as set forth.

3. In a typewriting machine, the combination of a carriage, a platen, a pair of line space levers arranged adjacent to the opposite ends of the carriage, said levers being of 130

different length and interchangeable, and mechanism actuated by said levers for rotating the platen, substantially as set forth.

4. In a typewriting machine, the combination of a carriage, a platen, line space mechanism for rotating the platen, a friction brake for holding the platen against movement, a line space lever, and means connecting said line space lever to said mechanism and to said brake to actuate said mechanism by the movement of the lever in one direction and to actuate said brake by a movement of the lever in another direction, substantially as set forth.

5. In a typewriting machine, the combination of a carriage, a platen, line space lever and mechanism for rotating the platen, a friction brake for holding the platen against rotation, and means actuated by said lever for operating said line space mechanism and said brake, said lever being movable to apply the brake independently of said line space mechanism, substantially as set forth.

6. In a typewriting machine, the combination of a carriage, a platen, line space mechanism for the platen, a detent for the platen, a line space lever, and means actuated by a movement of said lever in one direction to actuate said line space mechanism and by a movement of the lever in another direction to release said detent, substantially as set forth.

7. In a typewriting machine, the combination of a carriage, a platen, line space mechanism for rotating the platen, a detent for the platen, a friction brake for the platen, and a line space lever movable to actuate said line space mechanism and also movable to release said detent and apply said brake, substantially as set forth.

8. In a typewriting machine, the combination of a carriage, a platen, line space mechanism for rotating the platen, a detent for the platen, a friction brake for the platen, and a line space lever movable in one direction to actuate said line space mechanism and movable in another direction to release said detent and apply said brake, substantially as set forth.

9. In a typewriting machine, the combination of a carriage, a platen, line space mechanism for rotating the platen, a detent for the platen, a friction brake for the platen, and a line space lever movable both to actuate the line space mechanism and also to release said detent and apply said brake and to release said brake and permit the return of said detent to operative position, substantially as set forth.

10. In a typewriting machine, the combination of a carriage, a platen, line space mechanism for rotating the platen, a brake for the platen, a line space lever movable in one direction to actuate said line space

mechanism and in another direction to apply said brake, and a spring for returning said lever to a normal intermediate position, substantially as set forth.

11. In a typewriting machine, the combination of a carriage, a platen, a friction brake, a spring secured to the carriage, said brake being movably supported by said spring and normally held thereby in a position to permit the free rotation of the platen, and means for moving said brake into engagement with the platen and straining said spring, substantially as set forth.

12. In a typewriting machine, the combination of a carriage, a platen, a friction brake, a spring secured to the carriage and on which said brake is pivoted, and means for swinging said brake on its pivot into contact with the platen and for flexing said spring, substantially as set forth.

13. In a typewriting machine, the combination of a carriage, a platen, a line space lever for rotating the platen having an upright pivot, and a bent sheet metal bearing bracket for said lever provided with a part secured to the carriage and with a pair of projecting spaced bearing lugs for said lever pivot, substantially as set forth.

14. In a typewriting machine, the combination of a carriage, a platen, line space mechanism for the platen including an operating lever, releasing means for the carriage including a lever, and a push button supported by said line space lever and movable thereon for actuating said release lever, substantially as set forth.

15. In a typewriting machine, the combination of a carriage, a platen, a line space lever for rotating the platen, a lever for releasing the carriage, and a push rod seated in the pivot of said line space lever for actuating said carriage releasing lever, substantially as set forth.

16. In a typewriting machine, the combination of a carriage, a platen, a line space lever for rotating the platen, a lever for releasing the carriage, said line space lever having a hollow pivot, a push rod movable in said pivot and having a push button projecting beyond said line space lever, said push rod being connected to said carriage release lever, substantially as set forth.

17. In a typewriting machine, the combination of a carriage, a platen with journals, a ratchet wheel, pawl and operating means for turning the platen, a bearing sleeve for one of the platen journals rotatably adjustable on the carriage, and a pawl lifter secured to said bearing sleeve, substantially as set forth.

18. In a typewriting machine, the combination of a carriage, a platen with journals, a ratchet wheel, pawl and operating means for turning the platen, a bearing sleeve for one of the platen journals rotatably adjust-

- able on the carriage, a pawl lifter secured to said bearing sleeve, and a spring arm on said bearing sleeve for securing it in different positions, substantially as set forth. 45
- 5 19. In a typewriting machine, the combination of a carriage, a platen with journals, a ratchet wheel, pawl and operating means for turning the platen, a bearing sleeve for one of the platen journals rotatably adjustable on the carriage, and a pawl lifter and adjusting arm secured to said bearing sleeve between the end of the platen and the end of the carriage, substantially as set forth. 50
- 10 20. In a typewriting machine, the combination of a carriage, a platen, a ratchet wheel and pawl therefor located between the end of the platen and the end of the carriage, a pawl lifter, and an adjusting device therefor pivoted between the end of the platen and the end of the carriage and extending through the end of the carriage with its free end outside of the carriage, substantially as set forth. 60
- 15 21. In a typewriting machine, the combination of a carriage, a platen with journals, a ratchet wheel, pawl and operating means for turning the platen, a bearing sleeve for one of the platen journals rotatably adjustable on the carriage, a pawl lifter secured to said bearing sleeve, and a spring arm on said bearing sleeve having a snap engagement with the carriage and provided with a push button for releasing the spring from the carriage and adjusting said bearing sleeve, substantially as set forth. 65
- 20 22. In a typewriting machine, the combination of a carriage, a platen removably journaled therein, line space mechanism at one end of the platen, and a guard plate 70 which is movably mounted on the adjacent end of the carriage over the platen journal and extends in a direction to guard said line space mechanism, said guard plate having a part for holding the platen from removal from the carriage, substantially as set forth. 75
- 25 23. In a typewriting machine, the combination of a carriage, a platen, line spacing mechanism arranged between one end of the platen and the adjacent end of the carriage, and a guard plate movably mounted on said end of the carriage substantially parallel therewith and having a portion offset inwardly to overhang said line spacing mechanism, substantially as set forth. 80
- 30 24. In a typewriting machine, the combination of a carriage having upright end plates, of a platen, line space mechanism at one end of the platen, a sheet metal guard plate for said line space mechanism pivoted at one end to one side of the end plate adjacent to said line space mechanism and extending beside said end plate in a position to guard said line space mechanism, the other end of said guard plate having a releasable engagement with said end plate, substantially as set forth. 85
- 35 25. In a typewriting machine, the combination of a carriage, a platen, line space mechanism at one end of the platen including a toothed wheel, a guard plate for said line space mechanism pivoted to the carriage, and a detent for said toothed wheel secured to said guard plate, substantially as set forth. 90
- 40 26. In a typewriting machine, the combination of a carriage, a platen, line space mechanism at one end of the platen, a line space adjusting device, and a guard plate for the line space mechanism secured to the carriage and having stops for said line space adjusting device, substantially as set forth. 95

Witness my hand, this 14th day of May, 1906.
